UNITED STATES PATENT OFFICE.

DANIEL KOPS, OF NEW YORK, N. Y., ASSIGNOR TO KOPS BROTHERS, INC., OF NEW YORK, N. Y., A CORPORATION OF NEW YORK.

APPAREL CORSET.

Application filed February 15, 1922. Serial No. 536,648.

To all whom it may concern:

Be it known that I, DANIEL KOPS, a citizen of the United States, residing in the borough of Manhattan, city, county, and State of New York, have invented an Improvement in Apparel Corsets, of which the following is a specification.

This invention relates to an apparel corset and more particularly to a garment so constructed as to permit the body of the wearer to present an uncorseted appearance in conformity with the style or fashion prevailing at the present time. The invention more especially relates to a garment so constructed as to conform to the abdominal section of the body of the wearer and at the same time to permit the body to assume a natural position while providing more or less support for the body.

In carrying out the invention, the garment made in accordance therewith is constructed without straps or belts or other tension or adjusting devices which heretofore have been more or less commonly employed, and the front portions of the garment are so shaped as to conform to the body of the wearer and are preferably provided with relatively few stays, while the sides and back portions of the garment are fitted with stays in the usual manner to both shape the garment and provide support for the underlying portions of the body. In each front portion of the garment there is also provided a yielding gore member preferably V-shaped extending from the upper edge of the garment to a point approximately midway of the front steels whereby the necessary yielding effect is produced in the garment to permit the underlying portions of the body of the wearer to assume a natural position and at the same time to be afforded more or less support.

In the drawing:

Fig. 1 is a perspective view of a corset garment made in accordance with my present invention, and

Fig. 2 is an elevation on an enlarged scale showing the front members of one part of the garment.

Referring particularly to the drawing the corset garment made in accordance with this invention comprises front steel sections 10 and 11, the former of which is fitted with a series of spaced studs 12 and the latter with a corresponding number of sockets 13,

forming clasps by which the front edges of the garment are connected for use. The front steel sections also include depending extensions indicated at 14 and 15 respectively and below the ends of the front steels these extensions may be provided with a hook 16 for connecting the one to the other. Also as illustrated, these depending extensions of the front steel members may be provided with series of eyelets 17 and 18 through which a lace 19 is threaded to further connect and adjust the lower or skirt portions of the garment to position on the body of the wearer.

Each front portion of the garment comprises sections 20 and 21 of relatively great width, the former of which is connected to the front steel section, and the latter to the body of the garment, while these sections are connected to one another with an intermediate stay pocket 22 in which stay members 23 are inserted. These front sections 20 and 21 are so shaped as to make the garment conform to the body of the wearer without the additional use of straps or adjusting or other tension devices.

In the upper portion of the garment I employ a V-shaped gore member 24 which is preferably made of yielding fabric or other similar and suitable material. This V-shaped gore member 24 extends from the upper edge of the garment to a reinforcing strip 25 at the upper edge of the front section 20, and at its forward edge is connected to the front steel section by a line of stitching 26 and at its opposite edge to the stay pocket 22 by a line of stitching 27. The front steel section also extends an appreciable distance above the upper ends of the front steels as indicated at 28 and this upper extension may be provided with suitable clasps 29 by which the corresponding part of the other side of the garment may be connected thereto.

The lower portion of the garment forms a depending skirt as indicated at 30 and the garment may be fitted with suitable hose supporters 31 and 32, the former being connected to the end of the lower extension of the front steel section and the latter to the lower edge of the garment at the extremity of the stay pocket 22 or at the seam connecting the sections 21 and 22. In this form of garment I also provide tension straps 33 in the lower edge of the garment which are so

placed therein as to overlie the cut away sections 34 at the lower side edges of the skirts. It will be noted from the drawing that in the front sections of the garment 5 the customary stays are omitted, only one stay being employed, while at the rear of the garment the usual number of stays or supports are employed. Furthermore, this garment may be constructed in halves as is 10 customary in certain types of corset, or the back may be closed as is the case in other types of corset. In the use of the garment 15 it will now be apparent that when in place on the body of the wearer the abdominal section will be permitted to assume a natural position and at the same time more or less support will be afforded thereto and also to the busts, whereas the usual support is provided in the sides and back of the garment. 20

I claim as my invention:

1. In an apparel corset and in each front portion thereof, a front steel section, a front steel therein, the front steel section having 25 an extension above the upper end of the front steel, and a V-shaped gore of elastic fabric material in the upper portion of the garment adjacent the front steel section and the upper extension thereof adapted to permit the underlying parts of the body to assume a natural position and to be more or less supported therein. 30

2. In an apparel corset and in each front portion thereof, a front steel section, a front steel therein, the front steel section having 35 an extension above the end of the front steel, a front section secured to the front steel section, and a V-shaped gore of elastic material forming the upper end of the front section and secured thereto and to the front steel 40 section and the upper extension thereof to permit the underlying parts of the body of the wearer to assume a natural position and to be more or less supported therein. 45

3. In an apparel corset and in each front portion thereof, a front steel section, a front steel therein, the front steel section having an extension above the end of the front steel, a front section comprising two relatively wide members extending lengthwise 50 of the garment, and a V-shaped gore of elastic fabric material formed in the upper part of the member of the front section adjacent the front steel section attached thereto and to the front steel section in the upper extension thereof and also to the rear member of the said front section whereby the underlying parts of the body of the wearer are permitted to assume a natural position and are more or less supported therein. 55 60

Signed by me this 16th day of January, 1922.

DANIEL KOPS.
